DESIGN.

No. 31,565.

Patented Sept. 26, 1899.

E. W. McCASLIN.
SUPPLEMENTAL WHEEL RIM.
(Application filed Aug. 21, 1899.)

UNITED STATES PATENT OFFICE.

ELTON W. McCASLIN, OF CHICAGO, ILLINOIS, ASSIGNOR TO THE MORGAN & WRIGHT, OF SAME PLACE.

DESIGN FOR A SUPPLEMENTAL WHEEL-RIM.

SPECIFICATION forming part of Design No. 31,565, dated September 26, 1899.

Application filed August 21, 1899. Serial No. 728,032. Term of patent 14 years.

To all whom it may concern:

Be it known that I, ELTON W. McCASLIN, a citizen of the United States, residing at Chicago, county of Cook, State of Illinois, have invented and produced a new and original Design for Supplemental Wheel-Rims—that is to say, rims for converting wheel-rims of the clincher type into what are commonly known as "Crescent" rims—of which the following is a specification, reference being had to the accompanying drawings, forming part thereof.

In the drawings, Figure 1 is a side elevation of the supplemental wheel-rim embodying my design. Fig. 2 is a transverse section 5 of the supplemental wheel-rim, formed in accordance with my design.

The outer side or surface of the rim is substantially concave in cross-section, being formed by the curved line or segment A. Each side of the rim is also substantially concave in cross-section, as these side surfaces are formed by relatively short curved lines or segments B B. The inner side or surface of the rim is provided with a central rib C, which 5 is substantially convex in cross-section and between which and the sides of the rim are the

two shallow grooves D D. With such formation the transverse configuration or outline of the said rim will consist of the aforesaid segments A and B B and the three segments c and 30 d d, which latter are connected and merged into each other to form a series of reverse bends or curves, substantially as shown in Fig. 2.

The essential feature of my design consists 35 of the supplemental wheel-rim formed with outer and side surfaces, which are substantially concave in cross-section, and with an inner side or surface having a central rib, which is substantially convex in cross-section, and having also a shallow groove formed 40 at each side of said rib.

Having described my invention, what I claim as new, and desire to secure by Letters Patent, is—

The design for a supplemental wheel-rim substantially as herein shown and described.

ELTON W. McCASLIN.
